UNITED STATES PATENT OFFICE

WILLIAM R. ADAIRE, OF FOX CHASE, PENNSYLVANIA, ASSIGNOR TO NORTH AMERICAN
LACE COMPANY, OF PHILADELPHIA, PENNSYLVANIA

DESIGN FOR LACE

Application filed June 4, 1932. Serial No. 43,987. Term of patent 3½ years.

To all whom it may concern:

Be it known that I, WILLIAM R. ADAIRE, a citizen of the United States, residing at 7524 Verree Road, Fox Chase, in the county of Philadelphia and State of Pennsylvania, have invented a new, original, and ornamental Design for Lace, of which the following is a specification, reference being had to the accompanying drawing, in which the figure is a face view of a piece of lace showing my new design.

I claim:

The ornamental design for lace substantially as shown.

In testimony whereof, I affix my signature.

WILLIAM R. ADAIRE.
